UNITED STATES PATENT OFFICE.

ANTHONY FERBER, OF BUFFALO, NEW YORK.

DESIGN FOR A CALENDAR-STAND.

SPECIFICATION forming part of Design No. 26,026, dated September 15, 1896.

Application filed July 27, 1896. Serial No. 600,712. Term of patent 31 years.

To all whom it may concern:

Be it known that I, ANTHONY FERBER, a citizen of the United States, residing at Buffalo, in the county of Erie and State of New York, have invented and produced a new and original Design for Calendar-Stands, of which the following is a specification, reference being had to the accompanying drawing, showing a part thereof.

5 This design relates to the inclined stands or holders employed for holding or displaying a calendar pad or block.

10 The design is illustrated in the accompanying drawing, which forms part hereof, and which is a perspective view of a calendar-stand embodying my design.

15 The leading feature of my design consists in an inclined back plate, an upright wall or flange arranged at the raised end of the back plate, upright flanges or wings arranged at the ends of said upright end wall and standing at right angles thereto, and upright lips or flanges arranged at the base of the inclined back plate.

20 Referring to the accompanying drawing, A is the inclined back plate of the calendar-stand, and a is a foot depending from the raised end thereof.

a' a² are openings in the back plate.

B is the upright wall rising from the elevated end of the back plate, and b is an opening therein.

C represents the upright wings which flank the ends of the wall B and which are arranged parallel with the longitudinal edges of the back plate.

D represents the upright lips or flanges rising from the base or lower end of the back plate on opposite sides of its middle. The upper ends of these lips are curved outward.

e represents grooves or depressions arranged in the upper side of the back plate near the longitudinal edges thereof and parallel therewith.

What I claim is--

25 The design for a calendar-stand, substantially as herein shown and described.

Witness my hand this 24th day of July, 1896.

ANTHONY FERBER.
